UNITED STATES PATENT OFFICE.

FRED G. WHITE, OF KANSAS CITY, MISSOURI, ASSIGNOR, BY MESNE ASSIGNMENTS, TO THE ELECTRIC CLIPPER COMPANY, OF FREDONIA, KANSAS, A CORPORATION OF KANSAS.

HAIR-CLIPPER.

1,311,935.

Specification of Letters Patent.

Patented Aug. 5, 1919.

Application filed November 22, 1918. Serial No. 263,662.

To all whom it may concern:

Be it known that I, FRED G. WHITE, a citizen of the United States, residing at Kansas City, in the county of Jackson and State 5 of Missouri, have invented certain new and useful Improvements in Hair-Clippers, of which the following is a specification.

This invention relates to power hair clippers and more especially to that class to be 10 held and guided by an operator and driven through the instrumentality of a flexible shaft, from an electric motor or the like.

The specific object of the invention is to produce an efficient hair clipper of small, 15 compact, light and inexpensive construction, a further object being to provide means whereby the angle of the clippers may be changed to change the length of cut.

With these general objects in view and 20 others of a specific character, the invention consists in certain novel and useful features of construction and combinations of parts as hereinafter described and claimed; and in order that it may be fully understood, reference is to be had to the accompanying 25 drawings, in which:

Figure 1, is a top plan view of a power hair clipper embodying the invention.

Fig. 2, is a side view of the same.

Fig. 3, is a central vertical longitudinal section of the same, but with the clipping jaws in elevation.

Fig. 4, is a plan view of the clipping jaws and of the plate to which power is applied 35 to reciprocate the upper or movable jaw.

Fig. 5, is a central vertical section of Fig. 4, the section being taken transversely of the cutting blades.

Fig. 6, is a side elevation of the shaft of 40 the clippers.

Fig. 7, is a front end view of the same.

Referring now to the drawings, in detail, 1 and 2 respectively designate the lower or stationary and upper or reciprocatory cutting jaws of the clipper, said jaws being of conventional type in this class of appliance, and to guide the upper jaw in its reciprocatory movement the lower jaw is provided with a pair of upstanding studs 3 and the 50 upper jaw with alined slots 4 receiving said studs. The rear end of the upper jaw is tapered downward and rearwardly at 5, and said rear end is bifurcated at 6 to provide an opening for the reception of a lug 7

stamped out of and depending from a plate 55 8 resting upon the upper jaw 2 and provided with slots 9 through which the guide studs 3 project. The plate 8 is provided with an upwardly and forwardly projecting lug 10 provided with a longitudinal slot 11, 60 and at opposite sides of said arm with down turned lugs 12 bearing upon the tapered rear edge 5 of the upper jaw. Said plate is also provided with a recess 13 at its front edge, for a purpose which hereinafter appears.

A carrying plate 14 fits upon the lower jaw 1 rearward of jaw 2, and screws 15 extend through said carrying plate and jaw 1 to secure said parts rigidly together. The 70 carrying plate is provided at its rear edge with an upwardly and forwardly extending ear 16, the same extending parallel with lug 10 of plate 8, it being understood in this connection, that said lug and ear extend upwardly and forwardly or at an acute angle with respect to the plane of cutting operation. The ear is provided in alinement with the slot 11 of lug 10 with a threaded opening 17 wherein is screwed the reduced front 80 end of a tube 18, and journaled in said tube is a shaft 19 provided at its front end with a crank arm comprising a portion 20 and an antifriction roller 21, the portion 20 fitting snugly between the ear and lug of plate 8 85 and carrying plate 14 respectively, the antifriction roller 21 being engaged with the slot 11 of said lug, it being noticed in this connection by reference to Figs. 6 and 7, that the portion 20 of the crank arm is increased 90 in size at a point diametrically opposite the location of the antifriction roller to act as a counter-balance and hence insure smoother rotation of the shaft in its operation of the upper or reciprocatory jaw 2.

The shaft 19 is provided with a longitudinal bore 21^a and with a longitudinal keyway 22, opening into said bore for a purpose which hereinafter appears, and rearward of said shaft the bore of the tube is enlarged as at 23 and counter-bored to provide an internal channel or groove 24.

An enlargement 25 for the tube 18 is secured thereon by a pin 26 or may be cast integral with the tube, and projecting from 105 opposite sides of said tube at the point of enlargement is a pair of handles 27 equipped near their front ends with outwardly and

upwardly projecting gripping lugs 28 to enable the operator to hold the clippers more firmly in the hair cutting operation.

To exclude hair from the slots in the reciprocal jaw, underlying plate and other operative connections, a cap 29 fits over plate 8 and upon the reciprocal jaw, and is provided centrally with an arch or raised portion 30 receiving the lug 10 and the ear 16. It also fits around the tube 18 at the front end thereof. The opening in the rear end of the cap is in the form of a bifurcation, and secured to the rear face of the central portion of the cap is an inverted U-shaped spring 31, the upper portion of said spring being adapted to fit in a circular recess 32 in a nut 33 mounted upon the threaded portion of the tube 18, the nut thus serving as an abutment whereby said 20 spring shall cause the cap to exert a yielding pressure for holding the reciprocal jaw in proper shearing relation with the stationary or lower jaw. In order that this clamping action may be provided with the 25 minimum of friction, the cap is provided with one or more internal lugs 34 bearing upon the recessed front edge of plate 8, and with a rib 35 bearing upon the upper edge of the slotted lug 10, it being understood 30 that the engaging surfaces of parts 34 and 35 with the plate and lug thereof shall be perfectly smooth and parallel to eliminate friction as far as possible. It will also be seen that by holding the cap pressed down 35 with a yielding pressure, the jaws are maintained in proper shearing relation regardless of wear, and that appreciable wear may be taken up by increasing the tension of the spring by a slight forward adjustment of 40 the abutment or nut upon the tube.

Owing to the fact that the spring is secured to the cap and fits within the recess in the front end of the nut or abutment 33, and of the further fact that forward sliding movement of the cap is impossible due to upward and forward inclination of the jaws and plate 8, the cap can not become dislocated accidentally, it being understood, of course, that forward adjustment of the 45 nut tends by reason of the inclination of the jaws, to press the upper or movable jaw down upon the lower or stationary jaw, and thus makes it possible to effect sufficient forward adjustment of the cap to take up 50 or compensate for wear of the cutting jaws. As a precaution, however, against applying excessive pressure on the upper jaw, the ear 55 15 is provided with a rearwardly projecting stop lug 36 upon which the nut will impinge 60 before the spring ceases to impose a yielding resistance to the advance of the nut.

As a means of holding the jaws at a greater angle to the head in performing the cutting operation, an attachment in the form 65 of a pivoted bail is provided, this bail com-

prising a cylindrical portion 37 and a pair of sides or arms 38 pivoted at 39 to opposite sides of the cap, the arrangement being such that the rod portion 37 of the bail may be disposed against the underside of the lower 70 jaw not far from the cutting edge thereof or be swung from said position to a position underlying the nut. When in the latter position the bail is inoperative. When in the former position the bail will come in 75 contact with the head of the person whose hair is being cut and thus hold the cutting edges of the jaws at such an angle that the hair can be clipped longer than when the bail occupies its inoperative position. 80

The flexible shaft 40 of an electric motor or the like, not shown, is adapted to fit in the bore of shaft 19, and is interlocked with the same by being provided with a key 41 for engagement with the slot or key-way of 85 said shaft. The casing 43 at the end of the flexible shaft is equipped with spring catches 44 for engaging the counterbore or groove 24 of the tube to guard against accidental withdrawal of the flexible shaft from the 90 power transmitting shaft 19.

From the above description it will be apparent that I have produced a device of the character set forth possessing all of the features of advantage hereinbefore mentioned, and I wish it to be understood that while I have described and claimed the preferred embodiment of the invention I reserve the right to make all changes properly falling within the spirit and scope of the appended claims. 95 100

I claim:

1. A power hair clipper comprising a tube or stem, a stationary jaw secured to said stem and extending convergingly upward and forward with respect thereto, a reciprocal jaw mounted upon the stationary jaw and movable to coöperate therewith in a shearing cutting action, a power transmission shaft journaled in the tube, connections 110 at the front end of said shaft for transforming rotary movement thereof into reciprocal movement of the upper jaw, a cap fitting over the said power-transmitting connections and the front end of said tube, and yielding means tending to advance the cap and cause the same to hold the jaws pressed 115 yielding together.

2. A power hair clipper comprising a tube or stem, a stationary jaw secured to said stem and extending convergingly upward and forward with respect thereto, a reciprocal jaw mounted upon the stationary jaw and movable to coöperate therewith in a shearing cutting action, a power transmission shaft journaled in the tube, connections 120 at the front end of said shaft for transforming rotary movement thereof into reciprocal movement of the upper jaw, a cap fitting over the said power-transmitting con- 125 nections and the front end of said tube, and yielding means tending to advance the cap and cause the same to hold the jaws pressed yielding together. 130

- nections and the front end of said tube, yielding means tending to advance the cap and cause the same to hold the jaws pressed yieldingly together, and handles rigid with 5 the tube.
3. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft journaled in the tube, connections at the front end of said shaft for transforming rotary movement thereof into reciprocating movement of the upper jaw, a cap fitting over the said power-transmitting connections and the front end of said tube, an abutment adjustable on the tube toward and from the cap and provided in its front side with a circular recess, and a spring secured to the cap at the rear side thereof and engaging the recess of said abutment and tending to advance the cap and cause the clamping of the upper jaw yieldingly upon the lower jaw. 55
- 10 4. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft journaled in the tube, connections at the front end of said shaft for transforming rotary movement thereof into reciprocating movement of the upper jaw, a cap fitting over the said power-transmitting connections and the front end of said tube, an abutment adjustable upon the tube toward and from the cap, and a spring interposed between the cap and abutment for pressing the former yieldingly in a forward direction to clamp the jaws yieldingly together. 60
- 15 5. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft journaled in the tube, connections at the front end of said shaft for transforming rotary movement thereof into reciprocating movement of the upper jaw, a cap fitting over the said power-transmitting connections and the front end of said tube, an abutment adjustable upon the tube toward and from the cap, and a spring interposed between the cap and abutment for pressing the former yieldingly in a forward direction to clamp the jaws yieldingly together. 65
- 20 6. A power hair clipper comprising a tube, a shaft journaled therein and provided forward of the tube with a crank, a jaw extending upwardly and forwardly with relation to the tube, a plate secured to said jaw and provided with an upwardly projecting ear secured to the front end of the tube, an upper jaw fitting slidably upon the lower jaw, a plate mounted upon and movable with said upper jaw and provided with an upwardly projecting slotted lug engaged by said crank whereby rotation of said shaft shall effect reciprocating movement of said plate and upper jaw, a cap fitting over said ear and said slotted lug and crank and the front end of the tube and bearing slidably upon said lug and said plate, and yielding means tending to advance said cap and thereby cause the same to press said plate and hence said upper jaw yieldingly downward. 70
- 25 7. A power hair clipper comprising a tube and relatively movable jaws carried by the tube and extending upwardly and forwardly beyond the front end of said tube, a suitably journaled shaft connected to the upper jaw for reciprocating the same, means for holding the jaws clamped yieldingly together to maintain them in proper operative relation, and adjustable means for disposition against the underside of the lower jaw near the front end thereof to increase the angle at which the 75 jaws shall stand with respect to the head during the hair clipping operation. 80
- 30 8. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft 85
- 35 9. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft 90
- 40 10. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft 95
- 45 11. A power hair clipper comprising a tube or stem, a stationary jaw secured to said stem and extending convergently upward and forward with respect thereto, a reciprocating jaw mounted upon the stationary jaw and movable to coöperate therewith in a shearing cutting action, a power transmission shaft
- 50

In testimony whereof I affix my signature.

FRED G. WHITE.
